UNITED STATES PATENT OFFICE.

ALEXANDER A. KLEBERG AND SAMUEL HATT, OF BROOKLYN, NEW YORK.

DESIGN FOR A MONEY-BOX.

SPECIFICATION forming part of Design No. 20,703, dated April 28, 1891.

Application filed March 23, 1891. Serial No. 386,135. Term of patent 7 years.

To all whom it may concern:

Be it known that we, ALEXANDER A. KLEBERG, a subject of the Czar of Russia, and SAMUEL HATT, a subject of the Queen of Great Britain, both residing at Brooklyn, in the county of Kings and State of New York, have invented and produced a new and original Design for a Money-Box, of which the following is a specification.

Reference is to be had to the accompanying drawings, forming part of this specification, in which the figure represents a perspective view of a money-box embodying our new design.

The design consists in the configuration shown, the distinguishing feature of which is the cruciform figure and a body, the lines of which extend between the arms of the cruciform top.

The letter *a* indicates the top, and *b* the box,

the said top being cruciform, and the side marginal lines of the arms of said top are curved, opposite sides merging into the curves *a'* at their inner ends. The lines of the body *b* form curves *b'*, that are opposite the curves *a'* of the top, and the lines of the body *b* merge into those of the top *a* at points intermediate the curves *b'*, as indicated by the letter *b²*.

The minor features mentioned are non-essential, the design consisting in the cruciform top.

We claim—

The design for a money-box herein shown and described.

ALEXANDER A. KLEBERG.
SAMUEL HATT.
